UNITED STATES PATENT OFFICE.

JOHN KARTHEISER, OF AURORA, ILLINOIS.

CAR-DOOR-LOCKING MEANS.

Application filed May 16, 1923. Serial No. 639,339.

To all whom it may concern:

Be it known that I, JOHN KARTHEISER, a citizen of the United States, and a resident of Aurora, in the county of Kane and State of Illinois, have invented a certain new and useful Improvement in Car-Door-Locking Means, of which the following is a specification.

My invention relates to new and useful car door locking means, and more particularly to means for operating and for locking doors of railway box cars such as are used for shipping grain, autos, stock and the like.

The main object of the invention is to provide locking means for the door of a box car or the like with which said door can be locked in the ordinary closed position, and can also be locked in a partly open position to provide a slot for ventilation but which slot is too narrow for the entrance of a person.

Another object is to provide lever means acting in conjunction with the locking means for partly opening the door to provide convenient access to the hand for fully opening the door.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevation of an embodiment of my invention, in which the door is shown locked in partly open position;

Fig. 2 is an enlarged detail section on line 2—2 of Fig. 1;

Fig. 3 is an elevational view showing the door locked in closed position, and

Fig. 4 is an enlarged vertical section on line 4—4 of Fig. 3.

My invention is adapted for use on a railway car, a truck, or other similar means of transportation used for hauling grain, furniture, autos, stock, etc., and is especially adapted for use on railway box cars. The present form of invention has therefore been illustrated in connection with a railway box car 10 which is provided with a door 11 slideable in the guiding means 12 and 12' and which overlaps the frame post 13 and rests against the edge portion 14 of the door frame, as best shown in Fig. 2.

The particular form of construction illustrated in the drawings comprises a base plate or means 15 mounted on the car adjacent the edge portion 14 of the door frame, and a yoke member or embracing means 16 is mounted on said plate and with it is fastened to the car by means of bolts 17 passing through flanges 18 and 18' on the ends of said yoke member 16 and through said plate 15. A lever 19 is mounted between plate 15 and yoke 16 and is fulcrumed on a bolt 20 passing through a depressed portion 16' on said yoke. A bar 21 is pivoted on the car door, is receivable in said yoke, and is engaged by the lever 19 for partly opening said door in order that the hand may be conveniently entered between the door and the frame for further opening the door, and also for holding said bar and the door in various positions. This engagement of the lever with the bar may be effected in any suitable manner, and as shown in the drawings, is effected by means of notches 22 provided on said bar and by a pin 23 provided on the lever for engaging in said notches, the top of yoke 16 co-operating with said means to prevent the upward movement of said bar or withdrawal of said bar while said lever is in vertical or locked position, as shown in full lines in the drawings. To partly open said door it is merely necessary to swing the lever outward, as indicated in dotted lines in Fig. 1.

Means is provided for locking the lever in position, which means includes an outwardly extending portion or flange 24 on plate 15 and a co-operating portion or flange 25 on lever 19, and a sealing pin 26 provided with a slot 27 through which extends a rivet 28 fastened on the lever. Said sealing pin is movable downward into registerable openings in said flanges to hold said lever and associated mechanism in locking position, and suitable sealing means 29 is fastened through an opening 30 at the lower end of the pin to seal and lock said pin 26 in position.

It is apparent from the above disclosure that with locking means constructed according to my invention the pin 23 on the lever is engageable in one of the notches 22 on bar 21 and that said lever may be locked in position by means of the sealing pin 26 for locking the door in partly open position, as shown in Fig. 1; and that said pin 23 of the

lever is engageable in another of the notches 22 and may be locked in position by the sealing pin for holding the door in closed position, as shown in Fig. 3; and furthermore 5 that by withdrawing the sealing pin 26 the lever may be conveniently swung outward, as shown in dotted lines in Fig. 1, to partly 10 open the door and enable the hand to grasp the edge of the door and further open the same.

While I have illustrated and described the preferred form of construction for carrying my invention into effect, this is capable of variation and modification without departing 15 from the spirit of the invention. I, therefore, do not wish to be limited to the precise details of construction set forth, but desire to avail myself of such variations and modifications as come within the scope of the 20 appended claims.

Having described my invention, what I claim as new and desire to secure by Letters Patent is:

1. In combination with a car and a door 25 thereon, a member swingably mounted on one thereof, a lever mounted on the other thereof, means on said lever engageable with said swingable member for partly opening said door, means embracing said lever and 30 said member and being arranged to prevent release movement of said member while said lever is in locked position, and means for locking said lever while in engagement with said swingable member for locking said door 35 in either a closed position or in a partly opened position.

2. In combination with a car and its door, a bar pivoted to said door, yoke means mounted on the car for receiving said bar, a 40 lever connected with said yoke means and engaging said bar for partly opening said door, the upper part of said yoke means preventing removal of said bar from said lever while said lever is in its locked position, and 45 means on said lever and car for locking said lever while engaging said bar to hold said door in either a closed position or in a partly opened position.

3. In combination with a car and its door, 50 a base plate mounted on said car, a yoke mounted on said plate, a bar pivoted on said door and moving in said yoke, a lever mounted

ed on said plate for engaging said bar and holding it in position in said yoke, a sealing pin movably mounted with a slot and rivet 55 on said lever, and co-operating means on said lever and on said plate for receiving said sealing pin to lock said mechanism and therewith said door in position.

4. In combination with a car and its door, 60 a plate mounted on said car, a yoke mounted on said plate, a notched bar mounted on said door and moving between said yoke and plate, a lever mounted between said yoke and plate and having means engageable in either 65 one of the notches in said bar, and means on said lever and said plate for locking said lever in position with its engaging means in one of said notches to retain said bar and door in either one of several selective positions.

5. In combination with a car and its door, 70 a bar pivoted on said door, base means and superposed yoke means mounted on said car for receiving said bar, a member swingable 75 between said base and yoke means and engageable with said bar, an integral flange on said base means, and a co-operating integral flange and sealing member on said swingable member, said flanges having registerable openings for receiving said sealing member.

6. In combination with a car and its door, 80 a notched bar pivoted to the door, means mounted on the car for embracing said bar, 85 a lever connected with said embracing means and having a pin for engaging in a notch on said bar for moving said bar and therewith said door to partly open position, and means for locking said lever in position to 90 retain said bar and attached door in a predetermined position, the upper part of said embracing means preventing the upward movement of said bar and thereby its removal from the lever pin while said lever is 95 locked in position.

In testimony whereof I have signed my name to this specification in the presence of two subscribing witnesses.

JOHN KARTHEISER.
